ORTHODONTIC BAND CHECKER INSTRUMENT

Albert P. Ruggieri, Flourtown, Pa., assignor of fractional
part interest to Bernard D. Stalnaker, Philadelphia, Pa.

Filed Apr. 28, 1975, Ser. No. 572,003

Term of patent 14 years

Int. Cl. D24—02

U.S. Cl. D24—1 D

FIG. 1 is a front view of the orthodontic band checker instrument showing my new design;

FIG. 2 is a top plan view thereof;

FIG. 3 is a rear view thereof;

FIG. 4 is a bottom plan view thereof;

FIG. 5 is an end view thereof taken from the right as viewed in FIG. 1; and

FIG. 6 is an end view thereof taken from the left as viewed in FIG. 2.

I claim:

The ornamental design for an orthodontic band checker instrument, as shown.
